[57] **CLAIM**

The ornamental design for a telephone set base, substantially as shown and described.

DESCRIPTION

FIG. 1 is a top perspective view of a telephone set base, showing my new design;

FIG. 2 is a top plan view thereof;

FIG. 3 is a side elevation thereof, the side opposite is a mirror image of the side shown;

FIG. 4 is a rear elevation thereof;

FIG. 5 is a front elevation thereof;

FIG. 6 is a top perspective view of a modified embodiment of the telephone base illustrated in FIG. 1;

FIG. 7 is a top plan view thereof;

FIG. 8 is a side elevation thereof, the side opposite is a mirror image of the side shown;

FIG. 9 is a rear elevation thereof; and

FIG. 10 is a front elevation thereof.
